UNITED STATES PATENT OFFICE.

CARL O. YOUNGREN, OF DOWNING, WISCONSIN.

FOLDING UMBRELLA.

1,240,001.

Specification of Letters Patent. Patented Sept. 11, 1917.

Application filed May 15, 1916. Serial No. 97,599.

To all whom it may concern:

Be it known that I, CARL O. YOUNGREN, a citizen of the United States, residing at Downing, in the county of Dunn, State of 5 Wisconsin, have invented a new and useful Folding Umbrella; and I do hereby declare the following to be a full, clear, and exact description of the invention, such as will enable others skilled in the art to which it 10 appertains to make and use the same.

The present invention relates to certain new and useful improvements in umbrellas, and has for its object to provide a device of this character which embodies novel features of construction whereby it can be collapsed and packed into a small amount of 15 space, thereby enabling it to be carried in the pocket or packed without difficulty in a suitcase or trunk.

20 Further objects of the invention are to provide a folding umbrella which is simple and inexpensive in its construction, which can be readily expanded or collapsed, which is securely locked against accidental 25 collapsing when in use, and which has no delicate parts to break and get out of repair.

With these and other objects in view, the 30 invention consists in certain novel combinations and arrangements of the parts as will more fully appear as the description proceeds, the novel features thereof being pointed out in the appended claim.

For a full understanding of the invention, 35 reference is to be had to the following description and accompanying drawings, in which:—

Figure 1 is a vertical longitudinal sectional view through a folding umbrella, 40 constructed in accordance with the invention, portions being broken away, the umbrella being shown in a distended position.

Fig. 2 is a similar view, showing the umbrella in a collapsed position.

45 Fig. 3 is a detail view of the locking mechanism for holding the extensible ribs in an expanded condition.

Fig. 4 is a view similar to Fig. 3, showing the locking mechanism in the position 50 assumed when the umbrella is collapsed.

Corresponding and like parts are referred to in the following description and indicated in all the views of the drawings by the same reference characters.

55 In carrying out the invention the ribs of the umbrella are formed in inner sections 1

and outer sections 2, said sections having a sliding connection with each other, so that the outer sections 2 can be telescoped upon the inner sections 1 when the umbrella is 60 collapsed. The inner ends of the sections 1 are pivotally connected in the usual manner to a head 3 at the upper end of a sleeve 4. The outer end of each of the sections 1 is beveled at 1^a to avoid any sharp corners or 65 projections which would tend to catch upon and tear the fabric cover, and a downwardly extending keeper 5 is provided at a point slightly spaced from the said beveled end. Each outer section 2 is arranged to slide 70 against the lower face of the inner section 1, being received within the keeper 5 of the inner section, and being provided at a point spaced from the inner end thereof with an upwardly extending keeper 6 which slidably 75 receives the inner rib section 1.

The extreme inner end of each outer rib section 2, is provided with a bifurcated bearing 7 which is straddled by the bifurcated end 9 of the brace 10 and pivotally connected thereto by a pivot pin 8. The opposite end of the brace 10 is pivotally connected in the usual manner to a runner 11 which is 80 slidable upon the stick, said runner carrying pivoted latch members 12 which are 85 adapted to engage a shoulder 13 on the sleeve 4 when the umbrella is distended for use. Springs 14 engage the latch members 12 to normally hold them in operative position, although by pressing inwardly with 90 the fingers upon the rear ends of the latch members 12, the latter can be readily disengaged from the shoulder 13 of the sleeve 4.

Pivots mounted upon each of the pivot pins 8, and arranged within the bifurcated 95 bearing 7 of each of the outer rib sections 2, is a dog 15, said dogs being adapted to spring into engagement with notches 16 in the inner rib sections 1 when the outer rib sections are moved outwardly to the limit 100 of their movement. Pins or lugs 17 which project from the outer rib sections 2 are then in engagement with the keepers 5 of the inner rib sections 1, so that the outer rib sections 2 are securely held against sliding 105 movement in either direction.

The dogs 15 are each formed with an extension 18 which is engaged by a spring 19 to normally hold the dog in operative position, said springs 19 being clamped and retained in position by the lower portions of the keepers 6. As previously explained, the 110

forked outer end 9 of the brace 10 straddles the forked bearing 7 of the outer rib section 2, so that when the runner 11 is moved downwardly upon the stick in the customary manner to collapse the umbrella, and the braces 3 are folded against the outer rib sections 2, the forked end 9 of the said braces will be brought into engagement with the extensions 18 of the dogs 15 so as to swing 10 the latter into inoperative position. With the dogs 15 thus engaged from the notches 16, the outer rib sections 2 can be telescoped inwardly upon the inner rib sections 1, so as to decrease the length of the ribs by about 15 one half.

The umbrella stick is formed in two main telescoping sections 20 and 21, the upper section 20 being adapted to telescope entirely within the lower section 21. A shorter handle section 22 is telescopically mounted upon the lower end of the section 21, while the before mentioned sleeve 4 is adapted to telescope over the upper end of the section 21 when the umbrella is collapsed. In this connection it may be noted that the section 20 extends centrally through the sleeve 4 and is rigidly secured to the head 3 at the upper end of the sleeve, although there is a sufficient amount of space between the said sleeve and the section 20 for the reception of the upper end of the section 21 when the device is collapsed.

The lower extremity of each of the sections 20 and 21 is very slightly enlarged, as indicated at 20^a and 21^a, respectively, for engagement with interior ribs 22^b and 21^b on the handle 22 and section 21, respectively, to prevent the members from pulling apart. At points slightly spaced from the lower ends thereof the members 20 and 21 are each provided with a pair of diametrically opposed openings 24 which are adapted to receive heads 25 on the ends of U-shaped springs 26, said springs being compressed and inserted within the members. These heads 25 are adapted to extend through the openings 24 into engagement with notches 27 in the upper ends of the member 21 and handle member 22, thereby prevent-

ing accidental collapsing or telescoping of the members when in use. However, when it is desired to collapse the stick, it is merely necessary to disengage the heads 25 from the notches 27 by pressing inwardly upon the heads, and then telescope the several members of the stick upon each other, the member 20 fitting completely within the member 21, and the member 21 being in turn received within the handle section 22 and the sleeve 4. The entire umbrella can thus be 60 collapsed and folded very compactly, thereby enabling it to be easily carried in the pocket, or packed in a suitcase or trunk.

Having thus described the invention, what I claim as new and desire to secure by Letters Patent, is:—

A folding umbrella, including a stick, pivotally mounted ribs adapted to be folded against the stick and formed in slidably connected inner and outer sections, each outer section sliding against the lower face of the inner section and terminating at its inner end in a bifurcated bearing, a runner, braces connected at their inner ends to the runner and having their outer ends bifurcated to straddle the bifurcated bearings of the outer rib sections, pivot pins connecting the said bifurcated bearings of the rib sections and the bifurcated ends of the braces, and spring actuated dogs arranged within 80 the bifurcated bearings of the rib sections and mounted upon the same pivot pins which connect the braces to the rib sections, the inner rib sections being formed with notches adapted to be engaged by the dogs 85 when the ribs are extended, and the dogs being provided with rearward extensions which are engaged by the bifurcated ends of the braces to automatically release the dogs when the runner is moved to swing 90 the ribs against the stick.

In testimony whereof I have signed my name to this specification in the presence of two subscribing witnesses.

CARL O. YOUNGREN.
